(57) **CLAIM**

The ornamental design for a fixation device for a surgical robot system, as shown and described.

DESCRIPTION

3. Fixation device for a surgical robot system

3.1 : Perspective (bottom, left side)

3.2 : Perspective (front, right side)

3.3 : Right

3.4 : Left

3.5 : Front

3.6 : Back

3.7 : Top

3.8 : Bottom

The parts colored in white and delineated in dashed lines are for the purpose of illustrating portions of the fixation device for a surgical robot system which form no part of the claimed design.
